BUTTON AND LOCK

Oscar Baggerud, Jersey City, N. J.

Application December 31, 1937, Serial No. 182,767

1 Claim. (Cl. 24—108)

5 My invention relates to button fasteners, or locks, of the type using a multiple prong staple which penetrates the cloth and the barbed ends of which are terminated and locked in a special resilient locking plate in the rear. This invention is furthermore an improvement of my button lock covered by Patent No. 1,598,597.

An important object of my invention is to provide a simple locking device for fastening buttons without using a needle and thread.

10 A further object of my invention is to provide a multiple pronged staple which looks similar to the thread fastening ordinarily used.

15 Another object of my invention is to provide a method of fastening any two or four-hole button in a way which is more secure and lasting than the ordinary method using thread.

20 Other objects and advantages of my invention will be apparent during the course of the following description.

In the accompanying drawing, forming part of this specification, and in which like numerals are employed to designate like parts throughout the same,

25 Figure 1 is a plan view of a button with the staple inserted,

Figure 2 is a section along line 2—2 in Fig. 1,
Figure 3 is a plan view of the staple,

30 Figure 4 is a side elevation of the staple,
Figure 5 is a plan view of the flexible spacer,
Figure 6 is a plan view of the rear cover plate,
Figure 7 is a plan view of the split spring locking washer,

Figure 8 is a plan view of the cup-shaped bottom washer.

35 In the drawing, wherein for the purpose of illustration, is shown a preferred embodiment of my invention, the numeral 15 designates the button with four holes 16 and the staple 17.

40 Between the button 15 and the fabric 18 is located the flexible washer 19, and on the rear side of the fabric, referring to Fig. 2, is located the cover plate 20, the split spring lock washer 21 and the cup-shaped bottom washer 22. In Figures 3 and 4 are plan 45 and side views, respectively, of the staple 17 with two long prongs 23, barbs 24 and pointed ends 25. Transversely across the staple 17 is welded another short staple 26.

In Figure 5 is shown a plan view of the flexible washer 19 with two holes 21. In Figure 6 is shown a plan view of the cover plate 20 with two holes 28, and in Figure 7 the split spring lock washer 21 is shown in plan view. This spring washer 21 is 5 split in several directions along the lines 29 and 30 whereby is formed the aperture 31 through which the pointed and barbed ends of the staple 17 may be forced. The cup-shaped bottom washer 22 is shown in plan view in Figure 8, the edge 32 10 of this washer is crimped over the cover plate as shown in section in Figure 2.

The operation of my invention is simply as follows: The staple 17 is inserted through the holes 16 in the button, through the washer 19 15 and pierced through the fabric 18, the locking washer is next pushed on to the staple in such a manner that the pointed ends 25 of the staple 17 first go through the holes 28 of the cover plate 20 and then are pressed down between the splits 20 in the spring washer 21. By pushing the staple down as far as it will go a small lip of the spring washer 21 will be bent downwardly along the prongs 23 of the staple 17 and will glide into the catch or barb 24 of the staple. The staple is then 25 locked in place.

It is to be understood that the form of my invention, herewith shown and described, is to be taken as a preferred example of the same, and that various changes in the shape, size and arrangement of parts may be resorted to without departing from the spirit of my invention, or the scope of the subjoined claim.

Having thus described my invention, I claim:

A button and fastener of the character described comprising in combination a button with four holes, a locking member consisting of a hollow, button-shaped receptacle, a cover plate with guide holes covering said receptacle, a locking washer with spring jaws fastened inside of the receptacle 40 between it and the cover plate, a double pronged staple with barbed points connecting said button and locking members, and a second staple with two short stubs fastened crosswise to the first staple. 45

OSCAR BAGGERUD.
